UNITED STATES PATENT OFFICE.

HOWARD M. BAREER, OF STONINGTON, CONNECTICUT, ASSIGNOR TO C. B. COTTRELL & SONS COMPANY, OF STONINGTON, CONNECTICUT, A CORPORATION OF DELAWARE.

SAFETY GRIPPER MOTION FOR CYLINDER PRESSES.

Application filed January 22, 1925. Serial No. 4,012.

During the process of "making-ready" it is customary for the pressman to open the grippers and throw them back into their rotary carrier. The pressman frequently 5 neglects to turn the grippers back before starting the press, thereby causing considerable damage to the parts when the press is started. Also it frequently happens that 10 too much material is crowded under the grippers, thereby preventing them from closing properly, thus holding the tumbler cam out of position to be properly operated by its closing pin and thereby causing considerable damage to the parts from this 15 condition.

The object of my invention is to provide means for avoiding the damage above set forth by providing the gripper tumbler cam with a beveled leading edge and by making 20 the cam actuating pins endwise yielding and by making one of the pins laterally yielding.

A practical embodiment of my invention is represented in the accompanying drawings, in which—

25 Fig. 1 represents a detail side view of so much of a sheet handling machine as will give a clear understanding of my invention.

Fig. 2 represents a detail plan view of the same.

30 Fig. 3 represents a detail front view.

Fig. 4 represents a detail section taken in the plane of the line IV of Fig. 2.

A rotary carrier, in the present instance 35 a cylinder 1 is provided with a set of tumbler operated grippers 2, the shaft 3 of which is provided with a tumbler cam 4 having the usual straight groove 5 therethrough for the passage of the cam actuating pins 6 and 7, to be immediately described. This 40 tumbler cam 4 is yieldingly held in either its opened or closed position by the usual spring means 8 for yieldingly holding the grippers in either their opened or closed positions. The tumbler cam 4 is provided 45 with a beveled leading edge 9 along one side of the cam groove 5.

The tumbler actuating pin 6 for opening the grippers has a yielding endwise sliding movement in a suitable fixed support 10, 50 a spring 11 serving to yieldingly hold the pin 6 at the limit of its movement into the path of the tumbler cam 4.

The tumbler cam actuating pin 7 for closing the grippers has a yielding endwise sliding movement in a rocking support 12, 55

pivoted at 13 to a fixed support, a spring 14 being provided for yieldingly holding the pin 7 at the limit of its movement into the path of the tumbler cam. The rocking support 12 has a yielding movement by providing a spring 15 tending to hold the pin 7 at the limit of its bodily lateral movement toward the axis of the rotary carrier 1.

By providing the leading edge of the gripper tumbler cam with the beveled face 65 and by making the cam actuating pins endwise yielding, all damage to the parts, due to the failure of the tumbler cam being replaced in its proper position to cause the cam groove to register with the pins, is 70 avoided, the tumbler cam in its movement causing its beveled leading edge to engage the pin and push it endwise out of the way so that the cam will pass without breaking the cam, the gripper pin or the gripper 75 stand.

Also, by mounting the cam actuating pin which closes the grippers, in a yielding rocking support so that the pin may yield laterally as well as longitudinally, all damage to 80 the parts, due to the failure of the tumbler cam being moved to its proper position by the crowding of the material under the grippers to prevent the closing of the grippers, is avoided. In this case as the pin travels along the cam groove, the pin will be moved laterally away from the axis of 85 the carrier and thus prevent breakage of the parts.

It is evident that various changes may be 90 resorted to in the construction, form and arrangement of the several parts without departing from the spirit and scope of my invention; hence, I do not intend to be limited to the particular embodiment herein 95 shown and described, but—

What I claim is:

1. A safety gripper motion including a gripper tumbler cam and an endwise and laterally yielding cam actuating pin. 100

2. A safety gripper motion including a gripper tumbler cam and cam actuating pins, both being endwise yielding and one being laterally yielding.

3. A safety gripper motion including a gripper tumbler cam and cam actuating pins, one being endwise yielding and the other being laterally yielding. 105

4. A safety gripper motion including a gripper tumbler cam having a beveled lead- 110

- ing edge and a laterally yielding cam actuating pin adapted to be engaged and moved out of the way by said cam if the cam be out of position.
5. A safety gripper motion including a gripper tumbler cam, a yielding cam actuating pin and a yielding rocking support therefor.
6. A safety gripper motion including a gripper tumbler cam, an endwise yielding cam actuating pin and a yielding rocking support therefor.

In testimony, that I claim the foregoing as my invention, I have signed my name this 20th day of January, 1925.

HOWARD M. BARBER.
